DESIGN FOR A HEATER PLUG

Augustine H. Massey, Stratford, Conn.

Application March 27, 1947, Serial No. 137,955

Term of patent 3½ years

(Cl. D26—1)

To all whom it may concern:

Be it known that I, Augustine H. Massey, a citizen of the United States, residing at Stratford, in Fairfield County, and State of Connecticut, have invented a new, original, and ornamental Design for a Heater Plug, of which the following is a specification, reference being had to the accompanying drawing, forming part thereof.

Fig. 1 is a front elevational view of a heater plug showing my new design;

Fig. 2 is an edge elevational view thereof; and
Fig. 3 is a top plan view thereof.

I claim:

The ornamental design for a heater plug, substantially as shown.

AUGUSTINE H. MASSEY.
